UNITED STATES PATENT OFFICE.

DAVID S. RUNNELS, OF APPLETON, WISCONSIN.

VESSEL-CLEANING MACHINE.

1,076,066.

Specification of Letters Patent. Patented Oct. 21, 1913.

Application filed November 22, 1912. Serial No. 732,871.

To all whom it may concern:

Be it known that I, DAVID S. RUNNELS, a citizen of the United States, and resident of Appleton, in the county of Outagamie and State of Wisconsin, have invented certain new and useful Improvements in Vessel-Cleaning Machines; and I do hereby declare that the following is a full, clear, and exact description thereof.

10 My invention refers to vessel cleaners generally, its primary object being to provide a simple, effective, economical and durable means for washing, rinsing and, if desired, sterilizing such vessels, whereby they are 15 put in practically a germ-proof condition preparatory to serving as containers for liquids that are most sensitive and susceptible to contamination.

Specific objects of my invention are to 20 provide contractible and expansible scrubbing brushes whereby they may be readily inserted and withdrawn from the mouths of vessels to be cleaned, and also to provide in conjunction with said brushes an exteriorly arranged set for scrubbing the outer surfaces of the vessels; to provide means for positively rotating the brushes, it being understood that each set of interior brushes are shaped to conform to the contour and 25 corners of the vessels, whereby said vessel corners which are most susceptible to foreign deposits are thoroughly scoured; to provide a fluid ejector nozzle that is centrally disposed with relation to the group of brushes, 30 whereby the vessels are subjected to a spray incidental to a scrubbing operation; to provide a simple and economical valve-controlled fluid supply pipe that communicates with the nozzle, whereby hot, soapy water 35 and rinsing water is successively discharged into the vessel by movements of the valve from a normally closed position; to provide simple and economical means for supporting and chucking one or a series of vessels in 40 concentric relation with corresponding sets of brushes, whereby the vessels are held against rotation while they are scrubbed and cleansed; to provide a simple arrangement of levers in connection with the machine 45 whereby the various operations are controlled conveniently from a position assumed by the operator.

In selecting and illustrating one means of carrying out my invention I have incorporated a machine for washing a pair of vessels in the form of milk cans, but it should

be understood that the machine may be designed to operate upon one or a series of vessels, or it may be constructed to meet the requirements for cleaning containers such as milk bottles or analogous articles.

With the above and other minor objects in view the invention consists in certain peculiarities of construction and combination of parts as hereinafter set forth with reference to the accompanying drawings and subsequently claimed.

In the drawings Figure 1 represents a sectional elevation of a vessel-cleaning machine embodying the features of my invention, the 70 section being indicated by line 1-1 of Fig. 2, which machine is designed especially for cleaning milk cans or other vessels of large capacity; Fig. 2 is a longitudinal sectional view of the machine, the section being indicated by line 2-2 of Fig. 1; Fig. 3, a detailed plan view of the vessel-supporting and chucking means with parts in section to more clearly illustrate structural features; Fig. 4, an enlarged detailed sectional view 80 of the scrubbing brushes and their connected mechanism, the same being illustrated expanded in their working position within a can, the section being indicated by line 4-4 of Figs. 6 and 7; Fig. 5, a similar sectional 85 view of the brush mechanism, the section being taken upon a plane at a right angle to the plane upon which Fig. 4 is taken, the section being indicated by line 5-5 of Fig. 6; Fig. 6, a sectional plan 90 view of the brush mechanism, the section being indicated by line 6-6 of Fig. 4; Fig. 7, another sectional plan view of the said mechanism, the section being indicated by line 7-7 of Fig. 4; Fig. 8, an enlarged 95 sectional view of a fluid-controlling valve having the water supply tanks and pump diagrammatically illustrated in connection with the same, whereby one form of the circulating system is disclosed, and Fig. 9, a detailed cross-section of my preferred form of brush.

Referring by characters to the drawings, 1 represents a bed provided with vertically disposed boxes 2, each of which forms a 105 bearing for a sleeve 3 that is revolubly mounted about a liquid ejector nozzle 4, each of which, as shown, is non-rotatory and extends below the sleeve for a pipe connection 5, to a supply-pipe 6. As best shown in Figs. 110 2 and 8 the supply-pipe 6 communicates with a valve-casing 7 having a rocker valve

8 mounted therein. Communicating with the valve-casing 7 upon opposite sides of the supply-pipe 6 are a pair of feed-pipes 9 and 10 respectively. The feed-pipe 9, as indicated by dotted lines in the diagram Fig. 8, communicates with one of a pair of cylinders of a pump 11, a stretch of said pipe being extended from the cylinder to a supply-tank 12 which is arranged in this instance as a container for hot, soapy cleansing water. The supply-pipe 10 is similarly connected to the other cylinder of the pump 11 and a tank 12', which tank, in this instance, is provided as a container for rinsing water. The valve-casing 7 has also connected thereto return pipes 9' and 10'. The pipe 9', as expressed by dotted lines in the diagram, is connected to the tank 12 and its corresponding return pipe 10' is similarly connected to the storage tank 12'. Thus it will be seen that a pipe circuit is established between the pump and each tank, whereby the respective contents of said tanks may be directed into the supply pipe 6 by manipulation of the valve 8. It is apparent from the diagram that should the pump be continuously operated and the valve 8 be in its normal closed position, as shown, the feed supply-pipe is cut off from pipe 6. However the valve in this position has established communication between pipes 9 and 9' of the circulating system of the storage tank 12 and also between pipes 10 and 10' of the circulating system of the tank 12'. The pump will thus cause the fluid from tank 12 to flow from said tank into the pump cylinder and from thence it is discharged into the valve-casing and returned to the tank through pipe 9'. Simultaneously fluid contained in the tank 12' will be caused to circulate from said tank through pipe 10 to the valve-casing and from thence through pipe 10' back to the tank. Should it be desired to establish communication between the soapy, hot water supply tank 12 and the supply pipe 6, a slight movement of the valve 8 will cut off the return pipe 9' coincident to establishing communication between said supply-pipe 6 and pipe 9. Hence the pump will cause the hot, soapy cleansing water to flow from tank 12 and be forced from the mouth of pipe 9 into the mouth of pipe 6, the same being discharged from both of the ejector nozzles. It is also apparent that in a rinsing operation, should the position of the valve be reversed from that just described, the rinsing water will be admitted to the supply-pipe 6 and when the operator releases the valve lever 8', as shown in Fig. 2, the valve will return to its normal position through the action of a leaf spring 13 that engages said lever and serves to return the same to its normal position, cutting off the supply-pipe 6.

65 Mounted upon the lower end of each sleeve

3 is a beveled pinion 14 that meshes with a beveled wheel 15, the said beveled wheels, as shown in Figs. 1 and 2, being secured to a power-shaft 16 that is journaled in boxes provided at each end of the bed. The shaft 70 carries the usual drive pulley 17 that is controlled by a clutch member 18 whereby said pulley is locked to or freed from the shaft. The clutch member 18 is actuated by a pivoted arm 19 having pins that are adapted to engage the cammed end 20 of a lever 21, which lever is rigidly secured to a rock-shaft 22, the same being suitably journaled in ears with which the bed 1 of the machine is provided.

80 Mounted upon each sleeve 3 and in spline connection therewith is a head 23 having a downwardly extended grooved collar 24, each of which collars is adapted to receive pins that are carried by spanner arms 25, the said arms being mounted upon a rock-shaft 26 that is journaled in ears 27 that extend upwardly from the face of the table-bed. These arms are normally held downwardly by one or more coiled springs 28 which connect said arms and the bed. The rock-shaft 26 has also secured thereto an arm 29 that is linked to a foot-treadle 29, which foot-treadle is secured to the rock-shaft 22.

85 From the foregoing description it will be observed that when power is applied to the foot-treadle through its lever and link connections each head 23 will be caused to move upwardly upon its sleeve, in opposition to spring control, to the positions shown in Figs. 2, 4 and 5, this treadle movement serving also to actuate the clutch member 18, whereby power is applied to the shaft 16 from the pulley.

90 Referring to Fig. 4 of the drawings, the head is illustrated as being provided with upwardly extending ears 30, to which are pivoted ends of links 31, the opposite ends of said links being connected to arms 32 that have their inner ends pivoted to ears 100 33 that extend from the sleeve 3. The upper open end of the sleeve 3 is also provided with ears 33' that have pivoted thereto bottom brush sections 34, the outer ends of which brush sections are in hinge connection 105 with side wall brush sections 35 that have their lower ends pivoted to the outer ends of the arms 32. Hence a downward movement imparted to the head 23 will, through its link connections with the arms 32, cause 110 a retraction of the brush sections, whereby they will be drawn inwardly to the position indicated in dotted lines. It will also be observed that one of the bottom brush sections 34 is provided with an extension at 115 its outer end, whereby its tufts will fit snugly into the bottom corner of a vessel A, which vessel is in the form of a standard milk-can. One of the side-wall brush sections 35 is similarly provided with an upward ex- 120

125

5 tension which engages the bottom corner of the vessel to thus insure cleansing the entire surface, these opposite corner extensions of the brush sections being adapted to overlap when the said sections are collapsed.

10 In order to thoroughly scour the neck and flared mouth of the can I provide a pair of non-collapsible brush sections 36, which brush sections are secured to the head and adapted to engage the inner walls of the neck and mouth when the head is moved upwardly to its working position, the said non-collapsible brush sections conforming to the contour of the neck and mouth. The 15 curved walls connecting the body of the can and its neck, comprising the shoulder portion B, are scrubbed by correspondingly curved brush sections 37, which brush sections, as best illustrated in Fig. 5, have their lower ends pivoted between wings 38 that extend from the sleeve 3, the said shoulder brush sections being preferably arranged at right angles to the wall, bottom and neck brush sections. Fingers 39 extend inwardly 20 from the shoulder brush sections 37 for engagement with tappet-pins 40, 41, which tappet-pins are spaced apart and supported by tongues 42 that extend upwardly from the head 23 between the wings 38. Hence 25 it will be observed that when the head is retracted or drawn downwardly upon the sleeve, engagement of the tappet pins 41 with the fingers 39 will cause the shoulder brush sections to retract to the position shown in dotted lines Fig. 5, and when the head is moved upwardly to its working position the tappet pins 40 will engage the fingers 39 and thus expand said brushes to the position illustrated in full lines Fig. 5.

30 From the foregoing description it is apparent that when the vessel is placed in position for scrubbing the brushes are all retracted and hence said brushes can be readily inserted within the mouth of the vessel preparatory to movement of the head, whereby said brushes are expanded to a working position.

35 It is also desirable to cleanse the exterior surface of vessels and with this in view I provide two or more sets of brush members 43, the lower ends of which are provided with apertured shanks that are rigidly secured to studs 44, which studs extend from a ring portion 45 of the head 23, this ring portion being connected at intervals with the body of the head by webs 46, thus an interrupted or skeleton connection is formed, whereby drainage from the body of the can may be effected between the ring portion and body portion of said head. 40 Owing to the fact that the outer brush members 43 are also rotated with the head and are subjected to more or less twisting strain, it is preferable to provide an upper bracing hoop 47 for said brushes, which hoop rig-

45 idly connects the same at this end, the vessel or can being adapted to readily drop into position between said brush members. These outer brushes 43 may be arranged to conform to the outer walls of the can if desired and may also be constructed from 50 several sections.

55 The upper end of the ejector nozzle 4 extends beyond the sleeve 3 and is provided with an apertured tip 48 through which the supply of water is discharged in a spray, against the bottom and side walls of the vessel. In order to more effectively break up and distribute the discharged liquid into spray-like form, I have shown a revoluble deflector wheel 49 that is mounted upon a spindle carried by the cap 48, which deflector wheel is provided with vanes that receive the impact from the jets of water discharged through the cap, to thus rotate the same and cause the water to whirl in spiral formation.

60 In order to provide efficient vessel-supporting and chucking means, whereby said vessels are alined and locked against rotation with relation to the brushes, I provide a vessel support 50, which vessel support is in the form of a table having apertures through which the vessels are inserted, the apertures being provided with flared rims 51 that serve to direct vessels more readily into their respective positions. The vessel supporting table 50 is rigidly connected to standards 52 that extend upwardly from the bed 1, said standards being secured in socketed ears that constitute part of the bed. Surrounding the vessel apertures of the supporting table and extending from the lower face thereof are circular apertured water channels 53, which channels communicate with each other and are connected by a branch pipe 54 to the main supply pipe 6, the latter, as best shown in Fig. 2, being connected to the supporting table through a 100 bracket extension.

65 Referring again to Fig. 4, when the vessel is inserted through the supporting table and in position to be cleaned, the rim of its mouth is adapted to be engaged and centered by the inner face of a flared ring 55, which ring is revolvably mounted upon suitable ball-bearings that are seated in the ring portion 45 of the head. Thus a centering and supporting means is had at the mouth 115 end of the can, it being observed that owing to the ring 55 being loosely mounted upon the head said ring may remain at rest incidental to rotation of the head.

70 When the flanged bottom C of the can engages the rim aperture of the supporting table, it is apparent that said can will be centered in alinement with the ejector nozzle and in order to lock or chuck the can in this centered position I provide a pair of 125

oppositely disposed chucking jaws 56 having convexed faces that extend through apertures that are formed in the rims 51, the said jaws being pivoted to the supporting table. The opposite ends of the jaw members are formed with slotted ears 57 that are engaged by pins which extend from a chucking lever 58, the said lever being also pivoted to the table. Hence by this arrangement of chucking mechanism when the vessels are in place, movement of the chucking lever 58 to the position shown in Fig. 3 of the drawings will cause the chucking jaws 56 to move in opposite directions and thus simultaneously chuck or lock the vessels against rotation, pressure of the chucking jaws being opposed by suitable cushion strips 59 with which the rimmed apertures of the table may be provided. Thus the friction grip of the vessels will not only prevent the latter from rotating, but serve to center them in axial alinement with their ejector nozzles, whereby the brushes when rotated will effectually perform their function.

It is apparent from the foregoing description that this machine may be employed for washing bottles or any other containers with equal efficiency and that the machine is capable of being constructed with as many brush spindles as the conditions may warrant and also that I may in some instances dispense with the outside scrubbing brushes. Furthermore in straight or tapered wall vessels the curved shoulder brushes can be dispensed with and the wall and bottom brushes made to conform to the inner contour of the vessels, this arrangement being a more simplified example of the machine.

Referring to Fig. 9 of the drawings I have shown my preferred form of brush, which brush comprises a wood backing-piece 62 that is detachably secured to a permanent metallic strip 63 by a series of bolts 64, which pass through the backing piece. By this simple construction the brushes can be removed and renewed quickly and economically.

In the operation of the machine, it is obvious that after the vessels have been dropped into the apertures of the supporting table, they are chucked by a manual operation, the internal scrubbing brushes being then in a collapsed condition. The operator next presses the foot-treadle, which will cause the internal brushes to expand outwardly into their working positions, due to the heads being slid upwardly upon their respective sleeves by the lever mechanism. This treadle movement simultaneously throws the driving pulley into clutching engagement with the power-shaft and the gear connection between the sleeves and said power-shaft will thus cause said sleeve together with the brushes to rotate at the de-

sired speed. In the meantime the operator having depressed the valve handle 8', communication between the tank 12 containing soapy hot water and the supply pipe 6 is established. Thus this water is discharged from the heads of each ejector nozzle, in the form of a whirling spray which will evenly distribute the water about the surfaces that are now being scrubbed by the rapidly rotating brushes. After the scrubbing operation has been completed the position of the valve handle 8' is reversed and communication is thereby established between the rinsing water tank and said supply pipe 6, whereby the interiors of the cans are thoroughly rinsed, drainage of the water being effected through the drain channel that is formed between the head 23 and the mouth of said vessel. The operator then relieves the foot-treadle from pressure, whereby the springs 25' will cause the brushes to retract and simultaneously disconnect the power from shaft 16. Hence the brushes being brought to a standstill and the supply of water or washing fluid being cut off the cans can be readily stripped from the brushes after manipulation of the chucking lever 58 to unlock said chucking members 56. The cans are then lifted bodily from the supporting table. When the interior brushes are being revolved it is apparent that the exterior brushes 43 will rotate therewith and thus thoroughly cleanse the outside of the vessels, said brushes working in conjunction with jets of water which are discharged upon the face of the cans through the circular channels 53 that communicate with the main supply pipe 6.

I claim:

1. A vessel-cleaning machine comprising a fluid nozzle, a rotatory sleeve mounted upon the nozzle, a head in slidable union with the sleeve, interior and exterior fixed brushes carried by the head, collapsible and expansible brushes in link connection with the head, valve-controlled water-supply means in communication with the nozzle, and means for supporting and chucking vessels to be cleaned. 105

2. A vessel-cleaning machine comprising a fluid nozzle, a rotatory sleeve mounted upon the nozzle, a head in slidable union with the sleeve, external fixed brushes carried by the head, collapsible and expansible brushes in link connection with the head, valve-controlled water-supply means in communication with the nozzle, and means for supporting and chucking vessels to be cleaned. 115

3. A vessel-cleaning machine comprising a fluid nozzle, a rotatory sleeve mounted upon the nozzle, a head in slidable union with the sleeve, internal fixed brushes carried by the head, collapsible and expansible brushes in link connection with the head, 125

- valve-controlled water-supply means in communication with the nozzles, and means for supporting and chucking vessels to be cleaned.
5. A vessel-cleaning machine comprising a bed, one or more fluid nozzles supported thereby, sleeves revolubly mounted upon the nozzles, heads revoluble with and in slidable union with the sleeves, means for 10 adjusting the heads longitudinally of the sleeves, sectional brushes in hinge connection with said sleeves, links connecting the sectional brushes and heads, means for imparting rotation to the sleeves, a valve-controlled supply-pipe in communication with the nozzles, and means for holding vessels to be cleaned against rotation.
15. A vessel-cleaning machine comprising a bed, a stationary fluid nozzle supported thereby, a rotatory sleeve mounted upon the nozzle, a head in slidable union with the sleeve, means for sliding said head longitudinally of the sleeve, sets of brushes in hinge connection with each other and in 20 hinge connection with the sleeve, means connecting the brushes and head, a supporting and chucking means for the vessels to be cleaned, a driving gear for the head, and a valve-controlled supply means in communication with the nozzle.
25. A vessel-cleaning machine comprising
- a fluid nozzle, a rotary sleeve mounted upon the nozzle, a head in slidable union with the sleeve, means for imparting longitudinal movement of the head upon the sleeve, collapsible and expandable brushes in link connection with said head, a valve-controlled water supply means in communication with the nozzle, and means for supporting and chucking vessels to be cleaned. 35
7. A vessel-cleaning machine comprising a stationary fluid nozzle, a rotatory sleeve mounted upon the nozzle, a head in slidable union with the sleeve but rotatory therewith, bottom scrubbing brushes in hinge connection with the sleeve, side-wall scrubbing brush-sections in hinge connection with the bottom brush sections, links connecting the head and side-wall brush sections, other brush sections in hinge connection with said 40 sleeve, and contractible and expandible means carried by the head for said other brush sections. 45

In testimony that I claim the foregoing I have hereunto set my hand at Appleton 55 in the county of Outagamie and State of Wisconsin in the presence of two witnesses.

DAVID S. RUNNELS.
